UNITED STATES PATENT OFFICE.

GEORGE G. FLOYD, OF CHICAGO, ILLINOIS, ASSIGNOR TO AMERICAN STEEL FOUNDRIES, OF CHICAGO, ILLINOIS, A CORPORATION OF NEW JERSEY.

SIDE FRAME AND TIE-BAR CONNECTION.

1,390,434.

Specification of Letters Patent. Patented Sept. 13, 1921.

Application filed April 8, 1920. Serial No. 372,223.

To all whom it may concern:

Be it known that I, GEORGE G. FLOYD, a citizen of the United States, residing at Chicago, in the county of Cook and State of Illinois, have invented certain new and useful Improvements in Side Frames and Tie-Bar Connections, of which the following is a specification.

This invention relates to truck side frames and journal box tie bar connection thereto.

In my copending application, Serial No. 344,769, filed December 15, 1919, I have set forth at great length the causes and effects of compression, tension and bending stresses set up in a cast metal side frame, and which are peculiar to the cast type of side frame. In such case I disclosed a cast metal side frame having pedestal jaws for receiving separate journal boxes.

This present application relates more specifically to a cast metal truck side frame which has no pedestal jaws and which has no integrally formed journal box, but preferably has integrally-formed longitudinally-extending portions at the ends of the frame to which the standard Master Car Builders' journal boxes are bolted. So far as the compression, tension and bending stresses set up in the frame, and the means for overcoming same, are concerned, this application is the same as my copending application above mentioned. Accordingly, no repetition will be made of the subject matter claimed in the copending application, and only such points as are necessary to give a complete understanding of this present invention will be considered.

In my said copending application I have emphasized the value of transmitting forces through the upper web side of the tension member and the compression member by directly connecting the upper web side of the tension member to the compression member instead of transmitting such forces through the journal box jaws or receiving portions.

However, in the type of side frame disclosed in this application some mechanical obstacles are presented in securing the journal boxes to the frame in a manner to meet all requirements.

Accordingly, one object of this invention is to provide simple, efficient and reliable means for securing journal boxes to cast side frames, in which the web of the tension member is secured directly to the compres-

sion member at a point adjacent the box fastening or securing members.

Another object is to connect the journal box tie bar to the side frame in a simple and efficient manner to meet the requirements of the conditions imposed.

These and other objects are accomplished by means of the arrangement disclosed on the accompanying sheet of drawings, in which—

Figure 1 is a fragmentary side elevation of a truck side frame embodying my invention, a part of the side frame being broken away to show the journal box connecting means;

Fig. 2 is a fragmentary top plan view showing the connection between the tie bar and the tension member of the side frame; and,

Fig. 3 is a sectional view taken in the plane of line 3—3 of Figs. 1 and 2.

The various novel features of my invention will be apparent from the following description and drawings and will be particularly pointed out in the appended claims.

Referring to the figures of the drawings, it will be noted that I have shown a cast side frame having a tension member 10, compression member 11, columns 12 (only one being shown) and journal box receiving portions 13 cast in a single piece. In this particular case the tension and compression members are U-shaped in section and have their webs 14 and 15, respectively, at the upper sides of said members and connected to each other at a point 16 over the flange 17 which receives the journal box 18, which in this case is the standard Master Car Builders' journal box having the usual bolt lugs 19, 20, 21 and 22. The advantages of having the tension and compression members 10 and 11 formed and connected in the manner here shown, has been considered in detail in my said copending application. Suffice to say, in this connection, that by means of this arrangement excessive tension and bending stresses are obviated.

While improving the cast type of side frame in the manner indicated certain obstacles have been encountered in securing the journal boxes to the side frame in an efficient manner. For example, by having the web 14 of the tension member extend to the web of the compression member in a straight line, as shown in Fig. 1, for the reasons given, difficulty was

presented in placing the inner journal box bolt 23 in position for holding the journal box. In two other copending applications, Serial Nos. 372,220 and 372,221, filed April 8, 1920, I have overcome the difficulties mentioned by providing the webs of the tension and compression members with aligned openings for the reception of the inner journal box bolt. It may be preferable to secure the journal box to the side frame without puncturing the webs of the tension and compression members. To this end I have provided the arrangement disclosed in this case, in which the inner journal box bolt 23 is applied, in a different manner. It will be noted that the side frame flange 17, to which the journal box is attached, is provided with an elongated slot 24 below and slightly inwardly from the point of connection 16 between the webs of the tension and compression members. By providing the elongated slot, the inner journal box bolt 23 may be applied with the journal box in an inclined position, as indicated in dotted lines. After the bolt is applied to the journal box, the bolt and journal box are moved into normal vertical position, this being done after the head 25 of the bolt can pass under the web 14 of the tension member. As shown in full lines in Figs. 1 and 2, the inner bolt 23 is in its proper fastening position wherein the bolt head 25 is located behind spaced lugs 26 to prevent lateral movement of the lug. The head 25 of bolt 23, and also the head 27 of outer bolt 28, rest upon the flange 17, the bolts passing down through their respective journal box lugs and openings in a tie bar 29, the lower ends of the bolts receiving washers 30 and nuts 31.

In this case I have shown the journal box tie bar 29 connected to the web 14 of the tension member 10, the inner end of the tie bar being enlarged, as at 32, and terminating in a shoulder portion 33 which engages the under side of the web 14. Inwardly from the shoulder the tie bar is provided with a round threaded portion 34, which extends through an opening 35 in the web 14 of the tension member, the nut 36 being applied to the threaded end 34 of the tie bar for rigidly holding the tie bar in place. Interposed between the nut 36 and the upper surface of the web 14 of the tension member, is a nut lock 37, one flange 38 of which overhangs and embraces one side of the tension member, and the other flange 39 of which engages a side of the nut 36. In assembling the parts with this arrangement, the tie bar will not be set and secured in place until after the journal box and its bolts have been

placed in their normal positions. By means of this arrangement the tie bar is rigidly held in place for performing its function. The tie bar is bent intermediate its ends to form a horizontal portion at the under side 65 of the journal box and an inclined portion which extends upwardly toward the tension member of the side frame and at substantially right angles thereto. By means of this arrangement the journal box may be applied and fastened to the side frame in a simple, efficient and reliable manner without puncturing the webs of the tension and compression members.

By providing the connection between the 75 tie bar and the side frame, the use of a tie bar bracket is obviated. Such tie bar brackets cast integrally with the side frames as used heretofore are objectionable to a certain extent in that there is a tendency for 80 the metal to shrink or crank around the juncture of the bracket and the frame; also the average tie bar bracket adds from fifteen to sixteen pounds to the side frame, while the pivotal connection which I have provided adds only about three or four pounds to the weight of the side frame.

It is my intention to cover all modifications of the invention falling within the spirit and scope of the following claims. 90

I claim:

1. In combination, a truck side frame having a journal box receiving flange with an elongated slot therein whereby a securing bolt may be passed therethrough at an inclined angle, a journal box receiving said bolt in an inclined position after which the bolt and box may be moved into normal position, a tie bar connected to said box and having a threaded end, and a nut for engaging said threaded end for securing the tie bar to the side frame.

2. In combination, a truck side frame having a tension member with a web, a journal box tie bar having a threaded portion extending through said web, and a nut engaging said threaded portion for securing the tie bar in place.

3. In combination, a truck side frame, a journal box tie bar having a shouldered portion and a threaded portion adjacent thereto, and a nut engaging said threaded portion for securing the tie bar to the side frame, said shouldered portion and nut being on opposite sides of the portion to which the tie bar 110 is secured.

Signed at Chicago, Illinois, this 24th day of March, 1920.

GEORGE G. FLOYD.
